UNITED STATES PATENT OFFICE.

CHARLES DE LUKACSEVICS, OF NEWARK, NEW JERSEY.

CARBURETER.

1,196,669.

Specification of Letters Patent. Patented Aug. 29, 1916.

Application filed March 30, 1916. Serial No. 87,845.

To all whom it may concern:

Be it known that I, CHARLES DE LUKACSEVICS, a citizen of the United States, residing at Newark, in the county of Essex and State 5 of New Jersey, have invented new and useful Improvements in Carbureters, of which the following is a specification.

This invention relates to improvements in carbureters, proposing a carbureter of that 10 broad or general type wherein an absorbent distributing element, partially submerged in the liquid fuel, is arranged to deliver gasolene vapor to the air induced through the mixing chamber and is vertically movable 15 whereby to increase or decrease its submergence in the liquid fuel and a valve member is provided which operates in conjunction with the vertical movement of said absorbent element to regulate the degree of 20 its exposure to the air passing through the mixing chamber.

The principal object of the invention is to provide an exceedingly simple, efficient and reliable carbureter of the type described. 25 The invention consists in certain novel features of construction and combination which will appear as the description proceeds.

An embodiment of the invention is illustrated in the accompanying drawing, 30 wherein:—

Figure 1 is a vertical longitudinal sectional view of a carbureter in which the features of the invention are incorporated; 35 and Figs. 2 and 3 are detail vertical cross-sectional views through the air passage or mixing chamber showing the absorbent distributing element in its extreme positions.

Similar characters of reference designate 40 corresponding parts throughout the several views.

The fuel chamber 1 concentrically surrounds an air passage 2 from which it is separated by a cylindrical wall 3. The air 45 passage 2 provides a mixing chamber and is open at its upper end to the motor suction tube (not shown) to which the carbureter is connected by an attachment flange 4.

The air passage 2 has its lower or inlet 50 end of bell or flaring form as at 5 and is arranged above, and in axial alinement with,

an air inlet chamber 6 provided with a laterally directed inhaust tube 7. The chamber 6 has a partition 8 which provides a seat for a valve 9 employed to control the admission of air to the passage 2. The valve 9 is preferably spring loaded, being urged toward its seat by a helical spring 10 which at its lower end projects into a central depression of the valve 9 and at its upper end bears against a stop collar 11 fixedly mounted on a stem 12.

The stem 12 is threaded through the hub of a spider 13 arranged in the flaring inlet 5 and projects at its lower end beyond the chamber 6, terminating in a knurled head and having a threaded portion 14 adjacent said head. A lock nut 15 is mounted upon the threads 14 and bears against the base of the chamber 6. The nut 15 serves to hold the stem 12 against turning movement from any position to which it may be adjusted and also to hold the chamber 6 (which is preferably made as a separable casting) against the base of the fuel chamber 1. Obviously, 75 by turning the stem 12 in its threaded bearing in the spider 13 and thereby raising or lowering the collar 11, the tension of the spring 10 may be regulated as desired.

The wall 3 is provided at a suitable elevation with several horizontal rows of openings 16 which are preferably inclined inwardly and upwardly in order to deliver the gasolene vapor into the air toward the center of the ascending column and in the 85 same, i. e. upward, direction in which the air is moving.

The absorbent fuel distributing element 17 is of annular form and has a close surrounding fit on the wall 3, being slidable 90 lengthwise of said wall. The element 17 preferably has its outer circumferential face of inverted conical form whereby the exposure of said element to the liquid fuel will be increased by progressively greater increments as said element is moved downward into the liquid fuel. In this way, an exposure of the element 17 whereby said element will deliver an amount of liquid fuel sufficient for the maximum engine speed 95 100 may be obtained with a comparatively short downward movement of said element.

The element 17 in any operative position thereof will cover the openings 16. The communication of these openings with the air passage 2 is controlled by a ring valve 18 which has a relatively close fit against the inner face of the wall 3 and is slideable lengthwise of said wall. The valve 18 and the distributing element 17 are movable as a unit, and for this purpose, are connected by a cross-bar 19 whose ends project through vertical slots 20 in the wall 3. The valve 18 is provided with oppositely located upright ears 21 and the cross-bar 19 projects through openings in the ears 21 and is provided at its ends and as parts thereof with retaining screws 22 for the element 17.

As shown and preferred, the unitary operation of the element 17 and the valve 18 is correlated to the operation of the throttle valve 23 which is mounted in the upper portion of the air passage 2. The throttle valve 23 may be of butterfly form and operates the element 17 and the valve 18 by means of a link 24 extending between the cross-bar 19 and the valve 23. When the valve 18 has been lowered sufficiently to uncover any of the openings 16 gasoline vapor will pass through said openings and will be taken up by the ascending column of air in the passage 2. To facilitate the mixture of the fuel constituents, the stem 12 is provided at its upper end with a spreader 25 of inverted conical form.

The fuel chamber 1 may conveniently be a float feed chamber and is, therefore, shown as provided with a float feed mechanism 26 which may be of any suitable construction.

Figs. 1 and 2 show the throttle valve closed and the element 17 and valve 18 in their uppermost positions in which the valve 18 completely interrupts the communication of the opening 16 and the passage 2 and the element 17 is completely withdrawn from the liquid in the chamber 1. As the throttle valve is opened, the element 17 and valve 18 are lowered, and as the throttle valve is closed, the element 17 and valve 18 are raised. Obviously, the degree of downward or upward movement of the element 17 and valve 18 depends upon the degree of opening or closing movement of the throttle valve. It will be apparent that the aggregate area of the openings 6 uncovered by the valve 18 in its downward movement will progressively increase and that the submergence of the element 17 in the liquid fuel and, hence, the area of said element exposed to the liquid fuel, will progressively and proportionately increase. In this way, the amount of liquid fuel delivered into the passage 2 from the element 17 will be proportionate to the opening of the throttle. It follows that an accurate regulation of the amount of liquid fuel suitable for any speed

within the range of the engine may be obtained.

I claim—

1. In a carbureter, in combination, a fuel chamber, an air passage, an annular wall separating said chamber from said air passage, the fuel chamber surrounding the air passage, an annular absorbent fuel distributing element surrounding said wall and movable lengthwise thereof, said wall having openings over which said element extends, a ring valve arranged within the air passage and fitting against said wall, said ring valve controlling said openings, and connections between said element and said valve to provide for their unitary movement lengthwise of said wall.

2. In a carbureter, in combination, a fuel chamber, an air passage, an annular wall separating said chamber from said air passage, the fuel chamber surrounding the air passage, an annular absorbent fuel distributing element surrounding said wall and movable lengthwise thereof, said wall having openings over which said element extends, a ring valve arranged within the air passage and fitting against said wall, said ring valve controlling said openings, said wall having oppositely located vertical slots, and a cross-bar connecting said element and valve and projecting through said slots.

3. In a carbureter, in combination, a fuel chamber, an air passage, an annular wall separating said chamber from said air passage, the fuel chamber surrounding the air passage, and an annular absorbent fuel distributing element surrounding said wall and movable lengthwise thereof, said wall having openings over which said element extends and said element having its outer circumferential face of inverted conical form.

4. In a carbureter, in combination, a fuel chamber, an air passage, an annular wall separating said chamber from said air passage, the fuel chamber surrounding the air passage, an annular absorbent fuel distributing element surrounding said wall, said wall having openings over which said element extends and an inverted conical spreader arranged concentrically within said air passage below said openings.

5. In a carbureter, in combination, an air passage, a surrounding fuel chamber, an annular wall separating said passage and chamber and having fuel delivery openings, a spider at the lower end of said air passage, an air inlet chamber separably fitted under and in alignment with said air passage and having a horizontal partition formed with a valve seat, a valve co-acting with said seat, a stem projecting through the base of said air inlet chamber and through said valve, said stem being threaded into said spider and having a collar below said spider, a

helical spring surrounding said stem between said collar and said valve, said stem being threaded at its lower end, and a lock nut mounted upon the lower end of said

5 stem and engaging against the base of said air inlet chamber.

In testimony whereof I have hereunto set

my hand in presence of two subscribing witnesses.

CHARLES DE LUKACSEVICS.
